UNITED STATES PATENT OFFICE.

JOHN J. GALLAGHER, OF CHICAGO, ILLINOIS.

SWIMMING APPARATUS.

SPECIFICATION forming part of Letters Patent No. 732,405, dated June 30, 1903.

Application filed March 13, 1903. Serial No. 147,648. (No model.)

To all whom it may concern:-

Be it known that I, JOHN J. GALLAGHER, a citizen of the United States, residing at Chicago, in the county of Cook and State of Illinois, have invented certain new and useful Improvements in Swimming Apparatus; and I do hereby declare the following to be a full, clear, and exact description of the invention, such as will enable others skilled in the art to 10 which it appertains to make and use the same.

This invention is in the nature of means for assisting a swimmer in propelling himself through the water, and has for its object to provide an improved device of this character 15 which I denominate a "swimming apparatus."

With this object in view the invention consists in an apparatus of the character described, comprising a propeller-wheel, gearing connected up with the treadles to be operated by the feet of the swimmer for actuating the propeller-wheel, a saddle-bar mounted upon the bearing of the propeller-wheel, a saddle attached to the saddle-bar, and a suitable harness for attaching the whole apparatus to the body of the swimmer.

The invention further consists in the improved construction, arrangement, and combination of parts composing an apparatus, 30 all as hereinafter fully described, and afterward specifically claimed.

I have illustrated one form of apparatus in which my invention may be embodied in the accompanying drawings, in which—

35 Figure 1 is a view of the apparatus in front elevation, partly in section, together with a portion of the body and the limbs of a swimmer to which the apparatus is attached. Fig. 2 is a fragmentary detailed view, upon an enlarged scale, of the gearing. Fig. 3 is a detailed view of the means for securing the treadles to the feet of the swimmer.

Like numerals of reference mark the same parts in all of the figures of the drawings.

45 Referring to the drawings specifically, 1 indicates the body, and 2 and 3 the legs, of the swimmer.

In securing the apparatus to the body of the swimmer I propose in some instances to use a 50 harness provided with suspenders to run over the shoulders of the swimmer; but this I do not consider indispensable and have illustrated in

this instance a harness comprising a belt 4, from which depend straps or hangers 5, which connect with a saddle 6 and hold the saddle 55 firmly in position on the body of the swimmer. The saddle 5 I make very narrow at the crotch, inasmuch as the swimmer does not bear his weight upon it and it is desirable to interfere as little as possible with his movements, and 60 spread it out broadly from the hips backward, so that it may be firmly secured. The saddle is mounted upon a saddle-bar, preferably adjustable in length to accommodate persons of different lengths of limbs and different adjustments of the gearing, as hereinafter described, 65 said saddle-bar in this instance consisting of a tubular upper portion 7, mounted upon said lower portion 8 and secured in any adjustment by set-screw 9. Upon the lower portion 70 8 of the saddle-bar are two hubs 9 and 10, in which, as may at the time be desired, is journaled a crank-axle 11, provided with crank-arms 12 and crank-pins 13, the latter being adapted to receive flat soles or treadles 14, 75 secured to the feet of the operator by means of bands 15, said treadles having backwardly-pointed hook-like connections 16 to catch over the crank-pins and spring-pawl catches 17 to automatically spring into position, as in 80 Fig. 3, to hold the treadles upon the crank-pins. By releasing the pawls the treadles can be pushed forward off the crank-pins and may then be readily and quickly slipped off 85 the feet of the swimmer.

Upon the crank-axle 11 is secured a large vertically-placed bevel-crown gear-wheel 18, having two concentric circles of teeth 19 and 20, the former farther from the center than the latter, as clearly shown. When the parts 90 are assembled, the teeth of the crown-beveled wheel 18 engage with a bevel gear-wheel 21, secured on a shaft 22, journaled at the end of the part 8 and in line therewith, upon the outer end of which shaft is secured a propeller-wheel 23 of any suitable form or material. By operating the treadles the propeller is rotated and the body of the swimmer rapidly forced through the water. When it is desired to drive the propeller-wheel at the highest speed, the crank-shaft 11 is fitted in the hub 9, as shown in the drawings, and the teeth 19 engage with the teeth of the bevel-gear 21, but when for any reason it is desirable to de- 95 100

crease the speed the crank-shaft is removed from the hub 9 and journaled in the hub 10, which will bring the inner circle 20 of teeth of the wheel 18 into mesh with the bevel-wheel 21.

I sometimes provide a friction-roller at a suitable point upon the part 8, as shown at 24, to afford a bearing for the large wheel 18 and render its motion easier and steadier by 10 preventing friction.

The hook 16 might be secured directly to the band 15 without the intervention of the treadle 14. In either event the feet could be adjusted to the crank-arms by simply rubbing 15 them backward over said crank-arms, which motion would cause the spring-pawl catch 17 to yield to allow the crank-arm to slip into position, as shown in Fig. 3, the pawl springing back into its locking position as soon as 20 the crank-arms have passed it. With either construction it is only necessary in order to remove the foot from the crank-arm to slide it off the end thereof.

It being desirable that this apparatus shall 25 be as light as possible, it will probably be preferable to make all of the metallic parts of aluminum or some alloy thereof, such metals being exceedingly light and very strong.

Having thus fully described my invention, 30 what I claim as new, and desire to secure by Letters Patent, is—

1. A swimming apparatus comprising a saddle and saddle-bar, in combination with a harness for attaching the saddle-bar to the body 35 of the swimmer, a propeller-wheel journaled at the end of the saddle-bar, means for driving the propeller, in position to be operated by the feet of the swimmer, and detachable treadles therefor, substantially as described.

40 2. A swimming apparatus comprising a saddle and saddle-bar, in combination with a harness for attaching the saddle-bar to the body of the swimmer, means for adjusting the length of the saddle-bar, a propeller-wheel

journaled at the end of the saddle-bar, a bevel 45 gear-wheel on the propeller-shaft having two concentric circles of teeth, means for journaling the last-named wheel nearer to or farther from the propeller-wheel, and means for actuating the gearing in position to be adapted 50 to the feet of the operator in varying positions, substantially as described.

3. A swimming apparatus comprising a saddle, a harness for securing it to the body of the swimmer, a propeller-wheel connected 55 with the saddle, gearing for actuating the propeller-wheel, cranks for actuating the gearing, and means secured to the feet of the operator for readily engaging them with the crank-pin, said means comprising bands to 60 pass over the feet, rearwardly-projecting depending hooks secured to the bands, and spring-pawls normally in engagement with the ends of said hooks, substantially as described.

4. In a swimming apparatus, the combination 65 with a propeller, of a foot-operated mechanism for driving the same, and detachable treadles for actuating said mechanism, substantially as described.

5. In a swimming apparatus, the combination 70 with a propeller, of mechanism for actuating the same, crank-pins carried thereby, and treadles rotatably mounted upon said pins and detachable therefrom by lateral movement, substantially as described.

75 6. In a swimming apparatus, the combination with a propeller, of driving mechanism therefor, and crank-pins carried thereby, a treadle for each of said crank-pins, a hook carried by each treadle surrounding its respective pin, and a pawl normally closing each of said hooks, substantially as described.

In testimony whereof I hereunto affix my signature in presence of two witnesses.

JOHN J. GALLAGHER.
